UNITED STATES PATENT OFFICE.

CHARLES H. WOOD, OF SPRINGFIELD, MASSACHUSETTS.

FEEDING MECHANISM FOR SEWING-MACHINES.

SPECIFICATION forming part of Letters Patent No. 252,568, dated January 17, 1882.

Application filed November 14, 1881. (No model.)

To all whom it may concern:

Be it known that I, CHARLES H. WOOD, of Springfield, in the county of Hampden and State of Massachusetts, have invented a new 5 and useful Improvement in Sewing Machine Feed Mechanism, of which the following is a description and specification.

The object of my invention is to cause all the movements of the feed to be made positive and 10 without the aid of springs or any elastic force. I accomplish this by the mechanism substantially hereinafter set forth and illustrated in the accompanying drawings, in which—

Figure I is a reverse plan view of so much 15 of a sewing-machine bed as is necessary to show my improved mechanism as applied thereto. Fig. II is a transverse section of the same at line C of Fig. I. Fig. III is a side view of the feed-bar and feed, with a transverse section of the feed-lever, showing its engagement 20 with the feed-bar. Fig. IV is a reverse plan view or edge view of a portion of the feed-bar, showing a modification of the mechanism for taking up the lost motion of the feed-bar. Fig. 25 V is an end, side, and top view of a vertical wedge for taking up the lost motion of the feed-bar. Fig. VI is a section through the bed of the machine at line D, showing the feed-operating mechanism, and also the mechanism for 30 taking up lost motion of the feed-bar. Fig. VII is a longitudinal section of a portion of the feed-lever and the bed of the machine, showing a modification of the link by which the feed-lever is hung to the bed of the machine, and which gives the feed-lever its 35 vertical movement; and Fig. VIII is a reverse plan view, showing the cam attached to the vertical shaft which actuates the feed-lever, and the connection of the latter therewith. Fig. 40 IX is a reverse plan view of the bed of the machine, showing in full and in dotted lines the feed-operating lever and the link which secures it to the bed of the machine in the extreme horizontal positions which they 45 will occupy when in operation. Fig. X is a vertical longitudinal section at line E of Fig. IX, showing in full and in dotted lines the extreme vertical positions of the feed-lever and link when in operation.

In the drawings, A represents the bed of a sewing-machine, to which an ordinary pivoted

feed-bar, as 4, is attached, carrying the feed, as 15, and with which feed-bar an ordinary feed-lever, as 2, engages in a recess, as 5, made therefor, the feed-lever having a bearing on 55 both its edges in the feed-bar, and also for a short distance from one edge on both its sides; or the feed-lever may engage with the feed-bar in any other convenient manner, so that both shall move freely, and yet with little or no lost 60 motion between them.

A socket, as 9, is secured in the feed-lever, preferably near the end of the latter, in which socket an arm, as 8, of a link, as 7, has its bearing in such manner that the socket is free to 65 slide to and fro along the arm, and this link, as 7, is suitably pivoted to the lower side of the bed of the machine, preferably by a pin or screw inserted through the upper end of the link into a lug, as 1, cast on the lower side of 70 the bed, as shown clearly in Fig. II.

To provide for taking up any lost motion of the feed-bar occasioned by wear of the parts or otherwise, I cast two lugs, as 10 and 11, on the lower side of the bed, the lug, as 11, having one plane vertical side, against which the side of the feed-bar may bear, and the inside of the lug, as 10, is made inclined relatively to the adjacent vertical side of the lug, as 11, as shown clearly in Fig. VI, and a wedge-piece, 80 as 12, is made to fit the space between the inclined side of the lug, as 10, and the vertical side of the feed-bar 4, which extends between this wedge, as 12, and the lug, as 11. In order that this wedge may always retain its 85 proper vertical position, I provide a vertical elongated projection or boss, as 14, on the side of the wedge, which just enters and engages with a vertical slot in the lug, as 10, so that a screw extending through this slot and turned 90 into a threaded hole in the wedge may serve to adjust the wedge into a firm bearing against the feed-bar, as 4, and cause the latter to move always in the same plane. Instead of adjusting this wedge in a vertical direction, as shown 95 in Figs. I, II, and VI, I may adjust it horizontally by making one side of the feed-bar on an incline relatively with the adjacent side of the lug, as 10, made vertical, and the wedge adapted to slide lengthwise along the feed-bar, and 100 be secured thereto by the screw, as 16, turned through a horizontal slot in the wedge into a

threaded hole in the feed-bar, as shown clearly in Fig. IV.

Fig. VII shows a modification of the link which secures the feed-lever to the bed of the machine, in which the link, as 7, is provided with two spherical or partially spherical ends, the lower one having a bearing in the socket, as 9, attached to the feed-lever, as 2, and the upper end having a bearing in a recess in the lug, as 1, cast on the bed, and held in its socket securely by a cap, as *a*.

The operation of the feed-lever is substantially the same in both cases, as it is thereby pivoted to the bed of the machine, and when it is moved longitudinally in one direction by the action of the cam, as 32, on the vertical shaft, as 31, the link draws the feed-lever upward in the arc of a circle of which the center of its pivot in the lug, as 1, is the center, and the feed-bar and feed are thereby raised, and when the feed-lever is moved longitudinally in the opposite direction the bar is forced down in the same arc, and the feed-bar and feed are also moved down with it.

The horizontal movement of the feed-bar and feed in both directions is given by the side movements of the feed-lever upon its saddle-pivot, as 3, one of these movements being given when the feed is up, and after the lever has moved longitudinally in one direction, and the other being given after the lever has moved longitudinally in the opposite direction, and when the feed is down. In this manner four separate and positive movements of the feed-bar (which is adapted to move longitudinally

on its pivot) are obtained to operate the feed, obviating entirely the use of springs. The feed-lever and feed-bar always move vertically to the same extent, but the horizontal movement of both with the feed is controlled 40 or limited by the feed-lever saddle-pivot, as 3, which is attached to the ordinary stitch-regulating bar, as 30, which, with the pivot, is made movable to and fro along the feed-lever to control the side movement of the feed-lever. 45

It is evident that the elongated boss, as 14, on the side of the wedge 12 is not an essential feature, inasmuch as the wedge is perfectly operative without it, a little more trouble only being required to adjust it, its use being a matter of convenience rather than of necessity. 50

Having thus described my invention, what I claim as new is—

The combination, in a sewing-machine, of a feed-lever actuated by a cam and adapted to have a longitudinal and a lateral movement, a link pivoted at one end to the bed of the machine and at the other to said feed-lever, and a feed-bar carrying the feed and movably jointed to said lever, whereby, by the combined 55 longitudinal and lateral movements of the feed-lever and the movement of the said link pivoted thereto, the feed is forced to make all its movements both vertically and horizontally, substantially as described.

CHARLES H. WOOD.
